UNITED STATES PATENT OFFICE.

ELMER SAUVAIN, OF AGENDA, KANSAS.

ANTISPREADING DEVICE FOR RAILS.

1,207,223.

Specification of Letters Patent. Patented Dec. 5, 1916.

Application filed March 10, 1916. Serial No. 83,301.

To all whom it may concern:

Be it known that I, ELMER SAUVAIN, a citizen of the United States, residing at Agenda, in the county of Republic and State of Kansas, have invented certain new and useful Improvements in Antispreading Devices for Rails, of which the following is a specification.

The present invention relates to railway tracks and more particularly to new and useful improvements in anti-spreading devices for rails.

An object of my invention is to provide an anti-spreading device of the class described adapted to be positioned at intervals along a railway track between the ties to prevent lateral spreading of the rails which at the present time is the cause of many disastrous wrecks.

20 Another object of my invention is to provide an anti-spreading device of the class described which may be quickly and easily applied in operative position on a railway track without the use of tools, the only tool necessary being a monkey-wrench, it being possible for one man to apply numbers of the anti-spreading devices in a relatively short time. My invention is so constructed that it is possible to apply the usual insulating material to the device to prevent short circuiting of the rails which would render inoperative the block signal system.

25 A further object of my invention is to provide an anti-spreading device for rails, which is simple in construction, cheap to manufacture, strong and durable and effective in operation.

30 Other objects and advantages to be derived from the use of my invention will appear from the following detail description and the claim, taken with an inspection of the accompanying drawings, in which—

Figure 1 is an end sectional view of a railway track showing in side elevation my improved anti-spreading device in operative position, Fig. 2 is a top plan view of the same, and Fig. 3 is an enlarged perspective view of one end of the anti-spreading device.

35 Referring more particularly to the drawings, wherein similar characters of reference designate like and corresponding parts throughout the various views, 1 and 2 designate the rails of a railway track, the rails being of the usual shape and having the

bases 3, the rails being mounted on the usual ties of wood or metal designated 4.

As shown in the drawings my invention is applied to the usual type of railway track but I do not limit myself to such application, since by modification of a detail the device may be applied to street railway tracks, mine railways, and other non-permanent railways.

40 My invention preferably embodies an anti-spreading device comprising a major or body portion 5 the ends of which are widened as at 6, and upturned as at 7 to provide end shoulders. Strengthening webs 8 are formed beneath the enlarged portions 6 and extend upwardly along the shoulder 7 as indicated at 9. It will be apparent that it is preferable that the major portion of the anti-spreader and the webs be cast integrally.

45 As best shown in Fig. 1 the enlarged portions 6 are intended to lie beneath the rails 1 and 2, the bases of the rails receiving said enlarged portions. Detachable rail engaging elements are provided and comprise body portions 10 formed with flanges 11 along the opposite marginal edges thereof, said flanges being adapted to engage the vertical marginal edges of the shoulder 7, as shown to advantage in Fig. 3. The body 50 portion 10 is extended laterally to provide a rail engaging portion 12 slightly inclined upwardly to conform to the slanting upper surface of a rail base, best shown in Fig. 1. In order to retain the clamping element on 55 the shoulders I provide set screws 13 which extend through the body 10 of the clamping element into the shoulders. It is preferable that the flanged portions of the clamping elements be inherently resilient in 60 order to frictionally engage the shoulder whereby to prevent rattling of the device as a train passes thereover.

65 While I have shown my invention as applied to a tangent of a railway track it is of course understood that the device may be as readily applied to a curve and perhaps its advantageous features may be more apparent when used on a curve than on a tangent, however, it will be understood that 70 the exact location of the device does not affect it materially.

75 It will be readily apparent that should it be desired to use the device on a railroad employing the well known block sig- 80

naling system the insulating material commonly used may be easily inserted between the rail engaging portion 12, the rail base and enlarged portions 6. Of course, where the device is to be used in this manner the distance between the rail engaging portion 12 and the base 6 must be increased to accommodate the insulating material.

It will thus be seen that I have provided a simple anti-spreading device for railway tracks which, while it is particularly adapted for the purpose described is capable of a wide scope of application. One man may carry four or five of these anti-spreaders on a hand car and place the same in position where necessary along the railway.

From the above description taken in connection with the accompanying drawings, it is thought that a clear and comprehensive understanding of the construction, operation and advantages of my invention may be had, and while I have shown and de-

scribed my invention as embodying a specific structure, I desire that it be understood that I may make such changes on said structure as do not depart from the spirit and scope of the invention as claimed.

What I claim as new and desire to secure by Letters-Patent is:—

An anti-spreader for rails, comprising a body, the ends of said body portion being upturned to provide shoulder portions, a detachable rail member slidably mounted on the said shoulder comprising, a body portion, a section of the body extending laterally and slightly upward to conform to the slanting upper surface of a rail base, the marginal edges of the body being flexed to provide means for engaging the said shoulders and means for locking said clamping member to the shoulder for a purpose specified.

In testimony whereof I affix my signature.
ELMER SAUVAIN.
